(57) **CLAIM**

I claim the ornamental design for a hinged arm exercising device, as shown and described.

DESCRIPTION

FIG. 1 is a top perspective view of a hinged arm exercising device in an open configuration;

FIG. 2 is a top view of the hinged arm exercising device of FIG. 1 in the open configuration;

FIG. 3 is a left side view of the hinged arm exercising device of FIG. 1 in the open configuration;

FIG. 4 is a bottom view of the hinged arm exercising device of FIG. 1 in the open configuration;

FIG. 5 is a right side view of the hinged arm exercising device of FIG. 1 in the open configuration;

FIG. 6 is a rear view of the hinged arm exercising device of FIG. 1 in the open configuration;

FIG. 7 is a front view of the hinged arm exercising device of FIG. 1 in the open configuration; and,

FIG. 8 is a top perspective view of the hinged arm exercising device of FIG. 1 in a folded configuration.

The broken lines in the drawings are included for the purpose of illustrating an environmental structure and form no part of the claimed design.
